CLAIM

The ornamental design for ottoman, as shown and described.

DESCRIPTION

FIGS. 1-3 show the ottoman. From the top view, ottoman is generally square in shape.

FIG. 1 is a perspective view of the ottoman.

FIG. 2 is a top view of the ottoman; and,

FIG. 3 is a side view of the ottoman. The four side views are identical.

In each Figure, all surfaces not shown form no part of the claimed design.
